UNITED STATES PATENT OFFICE.

ROLAND C. HILTON, OF BOSTON, MASSACHUSETTS, ASSIGNOR TO WEST SIDE FOUNDRY COMPANY, OF COLONIE, NEW YORK, A CORPORATION OF NEW YORK.

AIR-PUMP.

1,204,273.

Specification of Letters Patent. Patented Nov. 7, 1916.

Application filed January 27, 1916. Serial No. 74,703.

To all whom it may concern:

Be it known that I, ROLAND C. HILTON, a citizen of the United States, residing at Boston, county of Suffolk, State of Massachusetts, have invented an Improvement in Air-Pumps, of which the following description, in connection with the accompanying drawing, is a specification, like characters on the drawing representing like parts.

10 This invention relates to air pumps and has for its object to provide a novel air pump which is compact in construction and yet has a comparatively large capacity.

15 A pump embodying my invention can be used for pumping air for various purposes, but the construction herein illustrated has been especially designed with reference to use on automobiles for pumping up the tires thereof.

20 In order to give an understanding of my invention I will first describe a selected embodiment thereof and will then point out the novel features in the appended claims.

Figure 1 is a vertical sectional view 25 through a pump embodying my invention; Fig. 2 is a sectional view taken at right angles to Fig. 1; Fig. 3 is a section on line 3—3, Fig. 2; Fig. 4 is a section on the line 4—4, Fig. 2; Fig. 5 is a section on the line 30 5—5, Fig. 3.

My improved pump comprises a base member 1 to which is secured a cylinder section 2 within which operates the piston 3. The base member and cylinder section may be secured together in any suitable way, but I have shown them as provided with flanges 4 and 5, respectively, which are bolted together, this being a convenient way to detachably connect these parts. The cylinder member 2 is provided at its end with an inlet valve 50 of any suitable or usual construction and with an outlet valve 6, said outlet valve having a nipple 7 associated therewith to which a delivery pipe 8 may be secured. The piston of the pump is actuated from a driving shaft 9 which is journaled in suitable bearings 10 and 11 formed on the base section 1, said shaft having an eccentric 12 thereon, the eccentric strap 13 of which is pivotally connected to the piston 3 at 14. The bearings 10 and 11 of the base section 1 extend into the latter, and the inner end faces 15 and 16 thereof are spaced apart a distance equal to the thickness of the eccentric 12, said end faces con-

stituting means for holding the eccentric in position. The eccentric 12 is firmly keyed to the shaft 9 and these end faces 15 and 16 of the bearings 10 and 11 also constitute means for holding the shaft 9 from longitudinal movement in its bearings. The shaft 9 is made of smaller diameter at one end than at the other, the portion 17 of smaller diameter also extending through the eccentric 12 so that the shoulder 18 between the portions of the shaft of different diameter abuts against one face of the eccentric.

In assembling the parts, the eccentric with the eccentric strap surrounding the same can be dropped into the space between the bearings and then the shaft may be forced into the bearings and through the eccentric. This is a simple construction by means of which the shaft is held from longitudinal movement by the coöperation of the eccentric and the end faces 15 and 16 of the bearings.

In order to make a compact structure I propose to make the piston 3 comparatively short, and in order to get a pump of the desired capacity I propose to make the cylinder of a large diameter relative to the length of the piston. In order that the pump may work properly it is, of course, necessary that the piston should be accurately guided in its movement, but because of its comparatively short length it is necessary to provide some auxiliary guiding means other than the contact of the piston with the walls of the cylinder to maintain the piston in proper alinement. The construction I herein provide for this comprises a plurality of guiding pins 19 which are secured to the underside of the piston 3 and depend therefrom, said pins extending into guiding apertures 20 formed in flanges or extensions 21 that extend laterally from the inner ends of the bearings 10 and 11. These pins 19 are of sufficient length so that they are not withdrawn from the apertures 20 even when the piston is in its highest position. These guiding pins 19 serve to hold the piston in proper alinement and prevent it from becoming twisted or cramped in the cylinder as might occur without these guiding pins because of the comparatively short length of the piston. The pump is lubricated by placing oil or other lubricating material in the chamber 24 in which the eccentric operates and to

prevent an excess of oil from being thrown up into the cylinder, I propose to employ a gasket 23 which is situated beneath the piston and which is supported by the flanges 5 22 that project inwardly from the walls of the base member 1 at each side of the bearings 10 and 11. This gasket is of such a thickness that the underside of the piston will come in contact with the same at each 10 downward stroke, and the presence of the gasket not only serves as a means for preventing an excess of oil from being thrown up into the cylinder during the rapid operation of the pump, but also serves as a 15 means for keeping all the parts of the pump properly lubricated. The gasket has an opening 41 therein through which the eccentric and eccentric strap operate, and said gasket has contact with these parts during 20 the operation of the pump. The gasket will be of felt or some other material which will absorb oil, and it, therefore, constitutes an oiling pad by which the parts moving therethrough are constantly oiled. At the 25 end of each down stroke, the lower edge of the piston will contact with the pad and will pick up some oil and thus the walls of the cylinder become sufficiently oiled without receiving an excess.

30 The shaft 9 may be operated in any suitable way. Where the pump is used on an automobile for pumping up the tires thereof, I propose to provide said shaft with a gear which is splined thereto and which is 35 adapted to be thrown into and out of mesh with a driving gear on some revolving part of the automobile mechanism. In the construction herein shown the shaft 9 has a gear 26 splined thereto which is adapted to 40 mesh with a driving gear 27. The gear 26 is moved longitudinally of the shaft to carry it into and out of mesh with the gear 27 by means of a shifting lever 28 which is 45 forked at one end and is provided with the lugs 290 that are received in a groove 30 in the hub of the gear 26. The gear-shifting lever 28 is pivotally mounted upon a supporting element 29 that is secured to the outer end 40 of the bearing 10; said bearing 50 being extended beyond the base member 1 for this purpose. This supporting member 29 is in the form of a metal strip bent to present the looped portion 31 that surrounds the hub 30 and to present the two arms 32 55 and 33 between which the lever 28 is received, said lever being pivotally mounted on a pivot pin 34 carried by the arms 32 and 33.

35 is a clamping bolt which extends through apertures in the arms 32 and 33 60 and which serve to clamp the loop 31 firmly about the hub 30. This bracket can be clamped on the hub in any desired position either longitudinally of the hub or angularly thereof so that it is possible to 65 place the gear-shifting lever 28 in any position in which it can be most easily operated and in which connections thereto can be more easily made. The arm 33 is shown as provided with a resilient extension 36 70 having a projection 38 situated to be engaged by the lever 28 as the latter is moved about its pivot. The resiliency of the extension 36 permits the lever to wipe by the projection 38 as said lever is turned about 75 its pivot and said projection co-operates with the lever to hold it in either of its two adjusted positions.

While I have illustrated herein a selected embodiment of my invention, I do not wish 80 to be limited to the constructional features shown.

I claim:

1. In a pump, the combination with a pump casing having a shaft bearing provided with a hub, of a driving shaft in said bearing, a piston operated by said shaft, a gear slidably mounted on the shaft, a bracket adjustably mounted on said hub and presenting a portion which surrounds the hub 90 and also presenting two arms, a gear-shifting lever situated between said arms and pivotally connected thereto, and means for clamping the bracket to the hub in any adjusted position, one of said arms being 95 longer than the other and being resilient, said arm carrying a projection adapted to engage the lever in different positions thereof and yieldingly hold it in adjusted position.

2. In a pump, the combination with a pump casing having a shaft bearing provided with a hub, of a driving shaft in said bearing, a piston operated by said shaft, a gear slidably mounted on the shaft, a bracket adjustably mounted on the hub, and a gear-shifting lever pivoted to said bracket and by which said gear can be shifted longitudinally of said shaft, said bracket having a resilient extension provided with a locking projection which is adapted to engage the lever and yieldingly hold it in different adjusted positions.

In testimony whereof, I have signed my name to this specification.

ROLAND C. HILTON.
